[57] CLAIM

The ornamental design for a bone milling template, as shown and described.

DESCRIPTION

FIG. 1 is a perspective view of a bone milling template showing our new design;

FIG. 2 is a top elevational view thereof;

FIG. 3 is a right side elevational view thereof, the left side being a mirror image thereof;

FIG. 4 is a bottom elevational view thereof;
FIG. 5 is a rear elevational view thereof;
FIG. 6 is a front elevational view thereof;
FIG. 7 is a perspective view of a bone milling template showing a second embodiment of our new design;
FIG. 8 is a top elevational view thereof;
FIG. 9 is a right side elevational view thereof, the left side being a mirror image thereof;
FIG. 10 is a bottom elevational view thereof;
FIG. 11 is a rear elevational view thereof;
FIG. 12 is a front elevational view thereof;
FIG. 13 is a perspective view of a bone milling template showing a third embodiment of our new design;
FIG. 14 is a top elevational view thereof;
FIG. 15 is a right side elevational view thereof, the left side being a mirror image thereof;
FIG. 16 is a bottom elevational view thereof;
FIG. 17 is a rear elevational view thereof;
FIG. 18 is a front elevational view thereof;
FIG. 19 is a perspective view of a bone milling template showing a fourth embodiment of our new design;
FIG. 20 is a top elevational view thereof;
FIG. 21 is a right side elevational view thereof, the left side being a mirror image thereof;
FIG. 22 is a bottom elevational view thereof;
FIG. 23 is a rear elevational view thereof;
FIG. 24 is a front elevational view thereof;
FIG. 25 is a perspective view of a bone milling template showing a fifth embodiment of our new design;
FIG. 26 is a top elevational view thereof;
FIG. 27 is a right side elevational view thereof, the left side being a mirror image thereof;
FIG. 28 is a bottom elevational view thereof;
FIG. 29 is a rear elevational view thereof; and,
FIG. 30 is a front elevational view thereof.
